EDUCATIONAL TOY STORE OR SIMILAR ARTICLE

Rita Buechner, Bronx, N. Y.

Application November 8, 1954, Serial No. 33,003

Term of patent 3½ years

(Cl. D25—1)

Fig. 1

Figure 1 is a fragmentary front perspective view of an educational toy store or similar article, showing my new design.

The base is rectangular, a portion of the rear being broken away in Figure 1 for convenience of illustration.

of being broken away in Figure 1 for convenience of illustration.

I claim:

The ornamental design for an educational toy store or similar article, as shown and described.
